UNITED STATES PATENT OFFICE.

DANIEL CARNEY, OF MERIDEN, CONNECTICUT.

SUSPENSION DEVICE FOR LAMPS.

SPECIFICATION forming part of Letters Patent No. 414,940, dated November 12, 1889.

Application filed July 15, 1889. Serial No. 317,555. (No model.)

To all whom it may concern:

Be it known that I, DANIEL CARNEY, of Meriden, in the county of New Haven and State of Connecticut, have invented a new Improvement in Suspension Devices for Lamps, &c.; and I do hereby declare the following, when taken in connection with accompanying drawings and the letters of reference marked thereon, to be a full, clear, and exact description of the same, and which said drawings constitute part of this specification, and represent, in—

Figure 1, a side view of the suspension device complete; Fig. 2, a front view of the same; Fig. 3, a detached view illustrating the operation of the cam upon the dog J; Fig. 4, the dog L, as engaged with its shoulder f of the cam; Fig. 5, a modification.

This invention relates to an improvement in the device by which lamps, chandeliers, &c., may be suspended from the ceiling and adjusted so as to rest at different elevations. Such suspending devices, generally speaking, consist of a spring-drum supported in a frame hung to the ceiling, with a cord or chain wound upon the spring-drum under the reaction of the spring, and to which cord the lamp is attached, and so that by drawing the lamp downward the drum will be rotated to wind the spring, and so that the reaction of the spring will aid in raising the lamp.

As the weight of the lamp or chandelier is variable, a locking device is desirable which will prevent the rotation of the drum when the lamp shall have been adjusted to the desired position, and so as to prevent the lamp from rising under the power of the spring overbalancing the weight of the lamp, or to prevent the descent of the lamp should that overbalance the spring. In the more general arrangement the spring is made with its initial power sufficiently great to support the lamp in its most elevated position. Then as the lamp descends the spring is wound, its power increasing accordingly, so that its tendency is to lift the lamp. Hence the locking device is applied to prevent the accidental or unintended ascent of the lamp; but in such case it is desirable that a locking device shall be applied, so that should the spring break, or in any way become inoperative, a locking

device may engage the drum, so as to prevent accidental or unintended descent of the lamp. It is to such locking devices that this invention particularly relates, it having for its object a simple locking device, automatic in its action; and it consists in the construction as hereinafter described, and particularly recited in the claims.

A represents the frame, provided with a suitable loop or eye B, by which it may be hung. On an axis C, supported in the frame, the spring-drum D is arranged in the usual manner for spring-drums in this class of devices. The spring (not shown) is secured by one end to the axis, which is stationary, and the other end to the drum, so that turning the drum in one direction will wind the spring. Then the reaction of the spring will serve to rotate the drum in the opposite direction.

To the drum a suitable cord or chain E is attached and wound thereon, extending downward. The lamp or thing to be suspended is attached to its lower end, and so that by pulling the said thing downward the drum will be rotated in one direction, so as to wind the spring. Then the reaction of the spring will operate to turn the drum in the opposite direction and wind the cord thereon, as usual in this class of devices. Fixed to or made as a part of the drum is a gear-wheel F, and in the frame a pinion G is arranged upon an axle H and so that said gear-wheel F will engage with the said pinion and impart rotation to the said pinion according to the direction in which the said gear turns with the drum.

On the axle H of the pinion G a cam I is made fast, so as to revolve with the pinion. This cam is constructed with a shoulder a in its periphery, with which a dog J is adapted to engage, the said dog hung upon an axis K, and so as to swing in a plane parallel with the plane of the said cam and so that the nose b of the dog may normally engage the said shoulder a, as represented in Fig. 2. The dog is preferably weighted, as at L, the tendency of the weight being to hold the nose of the dog down upon the cam I and into engagement with the shoulder a. The position of the shoulder a of the cam and the dog, as seen in Fig. 1, is in opposition to the reactive force of the spring, and so as to prevent such

reaction of the spring to rewind the cord thereon, but will permit the cam to escape from the dog when moving in the opposite direction. (Indicated by the arrow, Fig. 2, which arrow indicates the direction in which the drum is rotated in drawing the cord therefrom.) On the cam back of the shoulder *a* is a radial projection *d* of greater extent than the depth of the shoulder *a*. This projection *d* is adapted to strike upon the under side of the dog as the pinion rotates, and so that the pinion being rotated by the drawing down of the cord, so as to wind the spring, will throw the dog upward, as indicated in broken lines, Fig. 2.

As represented in Fig. 2, the dog *J* stands engaged with the shoulder *a* of the cam *I*, and so as to prevent the reaction of the spring in the drum; but if such reaction be required 20 the cord or chain is drawn downward, so as to turn the cam to the position indicated in broken lines, Fig. 2, which will cause the projection *d* of the cam to throw the dog out of reach of the shoulder *a*. Then the power 25 which produced such rotation of the cam being released, the spring reacts and imparts a quick revolution to the cam, so that the shoulder *a* will pass beyond the reach of the nose of the dog before the dog can fall into engagement with the shoulder. Consequently 30 the cam will continue rotation so long as the velocity of rotation of the cam is so rapid that after the dog has been thrown outward by the projection *d* of the cam, as represented in Fig. 3, the descent of the dog cannot be made until after the shoulder *a* shall have 35 passed beyond engagement with the nose of the dog, and as represented in broken lines, Fig. 3. At each of the rapid rotations of the 40 cam *I* the projection *d* will throw the dog out of possible engagement with the shoulder *a*; but if the rotation of the cam be retarded, as by holding upon the cord or chain, so that the movement of the cam be slow, then the dog 45 may drop into engagement with the shoulder *a*, as seen in Fig. 2, before that shoulder shall have passed out of reach of the nose of the dog. To provide a stop in the opposite direction, so that the descent may be prevented 50 except that descent be quickly made, a like dog *L'* is hung, preferably, upon the same axis *K* as the dog *J*, and in like manner weighted, as at *M*, the nose *e* of the dog adapted to rest on the periphery of the cam, and at 55 a point distant from the shoulder *a* an oppositely-directed shoulder *f* is formed, which may engage the nose of the dog *L'* when brought into contact therewith, and on the cam adjacent to the shoulder *f* is a projection *g*, of greater extent than the shoulder *f*, and, like the shoulder *d*, operates upon the dog *L'*, to prevent its engagement with the shoulder *f* under rapid rotation of the cam; but if the rotation of the cam be slow then the shoulder 60 *f* will engage the dog, as seen in Fig. 4, and thus prevent the rotation of the drum in the

opposite direction from that which is controlled by the dog *J*. In cases where the stop is required in but one direction a single dog only may be employed, as seen in Fig. 5, that figure representing the dog *L'* as omitted, and in that figure there are represented two shoulders *a* with corresponding projections *d* at opposite points, so as to make two points of engagement between the cam and the dog. There may be more of such points of engagement between the dog and the cam, if desired. By this construction the spring-drum is normally held against rotation in one direction, and from which it is released 80 by turning the drum in the direction opposite to that by which such engagement is made, and so that the projection of the cam will throw the dog out of reach of its shoulder on the cam, and then a quick rotation of the cam 85 permitted, so that the shoulder on the cam will pass out of reach of the nose of the dog before the dog can return into the path of the said shoulder.

The construction is simple and applicable 90 to suspension devices for many purposes for which such devices are adapted; but it is peculiarly adapted for lamps and chandeliers, because of its simplicity of construction, automatic action, and that it is not liable to de- 95 arrangement.

To prevent the impulse given to the pawl by cam projections throwing the pawl over to the reverse side, a stop, as *s*, may be provided on the frame projecting into the path of the 100 pawl, so as to prevent the possibility of its being thrown out of return to its proper position.

I claim—

1. In a suspension device, the combination 105 of a frame, a stationary axle therein, a spring-drum on said axle, provided with a cord or chain around said drum, a gear-wheel attached to said drum and so as to revolve therewith, a pinion supported upon an axle in the frame and arranged to engage with the said gear-wheel, so as to receive rotation therefrom, and a cam in connection with said pinion and so as to revolve therewith, the cam constructed with a shoulder on its periphery 110 and with a projection from the periphery of the cam near the shoulder, but of greater extent than the depth of said shoulder, with a dog hung to the frame to swing in a plane with said cam and adapted to engage said shoulder, but in the path of said projection, substantially as and for the purpose described.

2. The combination of a frame, a stationary axle therein, a spring-drum arranged upon said axle, carrying a cord or chain, a gear-wheel attached to and so as to revolve with said drum, a pinion hung upon an axle in the frame and arranged to engage with said gear-wheel so as to receive rotation therefrom, and a cam *I* in connection with said pinion and so 120 as to revolve therewith, the said cam constructed with shoulders *a* *f* in its periphery,

the said shoulders being oppositely directed, and the cam also constructed with projections $d\ g$ in its periphery respectively adjacent to said shoulders $a\ f$, but projecting to a greater extent than the depth of said shoulders, with two oppositely-directed dogs $J\ L'$, the one adapted to engage the said shoulder a and the other adapted to engage the said shoulder

f , and standing in the path of the respective projections $d\ g$, substantially as and for the purpose described.

DANIEL CARNEY.
